UNITED STATES PATENT OFFICE.

WILLIAM BLOW LE BOURGEOIS, OF CONVENT, LOUISIANA.

EGG-CARTON.

No. 911,051.

Specification of Letters Patent.

Patented Feb. 2, 1909.

Application filed July 31, 1907. Serial No. 386,399.

To all whom it may concern:

Be it known that I, WILLIAM B. LE BOURGEOIS, a citizen of the United States, residing at Convent, in the parish of St. James and 5 State of Louisiana, have invented a new and useful Egg-Carton, of which the following is a specification.

This invention relates to egg cartons.

The object of the invention is to provide a 10 simple and thoroughly efficient form of carton to be employed in the shipping and handling of eggs, the construction of which shall be such that the egg housed by the carton will not have any endwise movement therein, 15 and will thus be shielded from liability of breakage.

A further object of the invention is to provide a carton of this character which shall be simple in construction, cheap of manufacture, 20 and which may be used repeatedly by the exercise of ordinary care in handling.

With the above and other objects in view as will appear as the nature of the invention is better understood, the same consists in a 25 novel egg carton and combination of parts thereof hereinafter fully described and claimed.

In the accompanying drawings forming a part of this specification and in which like 30 characters of reference indicate corresponding parts,—Figure 1 is a view in perspective exhibiting the carton of the present invention, the parts being separated. Fig. 2 is a vertical longitudinal sectional view through 35 the carton.

The carton comprises two conical shells or members 1 and 2, which may be made of any suitable material, such as cardboard, pasteboard, or sheet metal, and have a lining 3 of 40 granular cork or other suitable padding which will operate to protect the egg against the liability of breakage when being shipped. One of the members, in this instance, the member 1, has its mouth 4 of greater diameter 45 than the mouth of the other member 2, so as to permit of the two members being telescoped and pass the egg from its ends, and prevent it from having any movement in the carton. These members are so constructed 50 that when once closed the egg is not pressed except at its ends.

As will be noted by reference to Fig. 1, the mouth portion of the member 1 is devoid of a lining, and this construction defines an interior circumferential shoulder against which 55 the inner end of the other member will abut when the two members are assembled, and thus limit inward movement of the two relatively to each other.

To hold the sections assembled two or 60 more sheet metal straps 5 are employed that are attached to the section 1 by rivets 6. These straps are designed to pass through keepers 7 that are riveted to opposite sides of the section 2, the straps being bent upon 65 themselves, as shown in Fig. 2, thus to hold the two sections assembled.

In the use of the carton, when the egg is positioned therein, the two end walls of the sections 1 and 2 are caused to abut against 70 the ends of the egg and are held in this position by the straps 5. To remove the egg it will only be necessary to straighten out the straps and separate the two sections.

It is to be understood that these cartons 75 are to be made in various sizes to accommodate hen eggs, duck eggs or the like, and as this will readily be understood illustration of more than one form is deemed unnecessary.

What is claimed is:—

An egg carton comprising two conoidal sections adapted for telescopic assemblage and having an interior yielding protecting surface that terminates short of the mouth of one of the sections to define an abutment or 85 shoulder to limit the insertion of the other section, bendable metal straps secured exteriorly of one of the sections and projecting beyond the mouth thereof and in approximate parallelism with the longitudinal axis of 90 the section, and metal keepers secured to the other section and inset from the mouth thereof and adapted to be engaged by the straps.

In testimony that I claim the foregoing as 95 my own, I have hereto affixed my signature in the presence of two witnesses.

WILLIAM BLOW LE BOURGEOIS.
